UNITED STATES PATENT OFFICE.

GEORGE L. HARPHAM, OF MAUPIN, OREGON.

COLLAPSIBLE BED-FRAME.

1,259,732.

Specification of Letters Patent. Patented Mar. 19, 1918.

Application filed May 10, 1917. Serial No. 167,677.

To all whom it may concern:

Be it known that I, GEORGE L. HARPHAM, a citizen of the United States, residing at Maupin, in the county of Wasco and State 5 of Oregon, have invented certain new and useful Improvements in Collapsible Bed-Frames, of which the following is a specification.

The object of this invention is to provide 10 a novel form of collapsible bed-frame, which, when in operative position, will be securely held against accidental collapse, and which, when in collapsed position, will occupy a small compass for storage, shipment, 15 or the like.

With this object in view, the invention 20 comprehends the novel construction, combination and arrangement of parts of a collapsible bed-frame, as will be fully herein- 25 after described in the specification, pointed out in the claims, and illustrated in the drawing.

In the accompanying drawings, I have 30 illustrated a form of embodiment of my invention capable of carrying out the underlying idea thereof. In the different figures of the drawing, like reference-characters indicate corresponding parts. The several figures of the drawings may be briefly described as follows:

Figure 1 is a top plan view of my collapsible bed-frame;

Fig. 2 is a side elevation thereof;

Fig. 3 is an end view thereof;

Fig. 4 is a section on the line 4—4, Fig. 1, looking in the direction of the arrows;

Fig. 5 is a section on the line 5—5, Fig. 4, looking in the direction of the arrows;

Fig. 6 is a side elevation of the bed-frame, 40 in partly collapsed condition; and

Fig. 7 is a side elevation of the bed-frame, entirely collapsed.

In Figs. 5, 6 and 7, the textile covering has been removed, more clearly to display 45 the parts of the bed-frame.

Referring, now, in detail to the drawings:

The collapsible bed-frame comprises, essentially, two end members 1, 1 and two side members 2, 2. These frame members are 50 preferably formed as longitudinal channel bars, and desirably of sheet metal stamped up to shape. When the bed-frame is set up in position for a person to recline thereon, the longitudinal side flanges 3 occupy a 55 horizontal position, as shown in Fig. 4.

Each of the side frame-members 2, 2 is made, as shown, in two sections, each overlapping at their inner adjacent ends, as shown, and are provided with a hinge 4. The two sections of each of said frame-members 2 are made of slightly different widths, whereby said overlapping ends may nest closely one inside the other, as shown, perhaps, best in Fig. 4.

To prevent accidental separation of said sections, *i. e.*, movement thereof on their hinges, when the bed-frame is set up in operative position, pivoted keepers 5 are provided, one thereof being furnished for each two sections, and being pivoted to one of 70 said sections adjacent the overlapping ends thereof. In Figs. 4 and 5 the keeper 5 is shown swung into operative position, so as to maintain the two sections against accidental movement on their hinge 4. 75

Carried by each of said sections of the side-members 2 is a leg 6 pivoted at 7 to the inner surface of said member. That end of the leg nearer the pivot 7 is preferably beveled, as shown at 8, and, when the leg 80 is in operative or upright position, said end thereof projects through a cut-away portion 9 in the top flange 3, and one longitudinal edge of said leg bears against one of the walls of said cut-away portion, as shown 85 in Fig. 4. The leg, when in operative or upright position, also projects through a cut-away portion 10 in the lower flange 3 of the side frame-member 2. The cut-away portion 10 is of such length that, when the leg 90 is folded in so as to lie flatly against the inner surface of the side frame-member 2 (as shown in dotted lines in Fig. 4), the outer end of said leg will clear the inner end wall of said cut-away portion. Each 95 of said legs 6 is preferably provided with a longitudinal, right-angled flange 11, which, when the leg is in operative position, as shown in full lines in Fig. 4, abuts the outer end wall of said cut-away portion 10. 100

A pair of links 12, 12 hinged together at their adjacent ends, as shown at 13, are pivotally connected, at their other ends, to the leg 6 and to the inner surface of the side frame-member 2, as shown at 14, 14. One 105 of said links 12 is provided with a toe 15 bent at right angles to the link and adapted to bear upon the other link near the hinged-point thereof, so as to limit movement, in one direction, of said links on 110

their hinge. But any other form of stop may, of course, be used. Each pair of said links 12, 12 constitutes a brace for the leg 6, as is obvious, and prevents collapse of 5 said leg when in operative position.

The side frame-members 2, 2 and the end frame-members 1, 1 are pivotally connected together in a peculiar manner, to accomplish a particular function. That is to say, the 10 manner of pivoting is such that the flanges of the side frame-members 2, 2 are spaced from the flanges of the end frame-members 1, 1, as shown most clearly in Figs. 2, 3 and 4. The arrangement is such that one of the 15 longitudinal flanges 3 of one of the side frame-members 2 (as shown in Figs. 3 and 4), at the point of pivotal connection of said member 2 with the end frame-members 1, 1, is midway between the two flanges of the 20 members 1, 1. The other side frame-member 2 is similarly positioned (as shown in Fig. 2). It is to be noted, however, that, while it is the lower flange 3 of the member 2 shown at the left-hand side of Fig. 3 that 25 is disposed midway between the two flanges of the end-members 1, 1, it is the upper flange 3 of the other member 2 shown at the right-hand side of Fig. 3 that is disposed midway between the two flanges of the end-members 1, 1. Pivot-pins 17 project 30 through the flanges 3 at adjacent ends of the members 1, 1 and 2, 2, and spacing-members 16, through which said pivot-pins also project, are disposed between the flanges 3 of 35 the members 1, 1 and 2, 2, at adjacent ends thereof. The members 1, 1 and the members 2, 2 are, preferably, of the same width. The peculiar arrangement, just described, of the flanges 3, 3 of the side-members 2, 2 with 40 respect to the flanges 3, 3 of the end-members 1, 1, and the arrangement of the side-members 2, 2 in different horizontal planes, insure that, when the bed-frame is collapsed, and folded, the parts will lie closely together and occupy a minimum space. 45

A textile covering 17 secured to bars 18, 18 may be provided, and the bars may be connected with the end frame members 1, 1 by retractile springs 19, as shown in Figs. 50 1 and 4.

In operation, in "knocking down" or collapsing the bed-frame from the position thereof shown in Figs. 1 to 4 to the position shown in Fig. 7, the links 12 are folded inward and the legs 6 moved toward the side frame-members 2, 2 until said legs and links occupy a position flatly against the side frame-members 2, 2, as shown in dotted lines in Fig. 4. Theréupon, the keepers 15 are 55 swung to release the sections of the side frame-members 2, 2 for movement on their hinges 4, 4; whereupon said sections of the side-frame members are moved, as shown in Fig. 6, the parts assuming the positions 60 shown in Fig. 6. Then, the end frame-mem- 65

bers 1, 1 are grasped and moved toward each other, the parts closing up into the position shown in Fig. 7.

While I have described with great particularity a concrete embodiment of my invention, it will be understood that departures from the physical presentment may be made, especially in matters of detail, so long as such changes come within the scope of the appended claims and the spirit of the invention. 70 75

Having thus fully described my invention and the operation thereof, the many advantages thereof will be apparent, especially to those skilled in the art to which it pertains. 80

Having thus fully described my invention, what I claim as new and desire to secure by Letters-Patent is:

1. A collapsible bed-frame including side-members formed as longitudinal-channel bars having longitudinal flanges, and legs carried by each of said side-members and pivoted to the inner surface thereof, one of said flanges having longitudinally-extending cut-away portions, through which said legs project when in operative position and providing a clearance space when the legs are swung to an inoperative position, so as to lie flatly against the inner surface of said side-members, between the flanges thereof. 95

2. A collapsible bed-frame including side-members formed as longitudinal-channel bars having longitudinal flanges, and legs carried by each of said side-members and pivoted to the inner surface thereof, one of said flanges having longitudinally-extending cut-away portions, through which said legs project when in operative position and providing clearance space when the legs are swung to an inoperative position, so as to lie flatly against the inner surface of said side-members, between the flanges thereof, each of said legs being provided with a longitudinal flange bearing against one of the end walls of said cut-away portion when the leg is in operative position. 105 110

3. A collapsible bed-frame comprising side-members and end-members formed as longitudinal-channel bars having longitudinal flanges, said side- and end-members, at adjacent ends, being pivoted together, and the flanges of said side-members, at the pivoted ends thereof, being spaced from the flanges of the end-members. 115 120

4. A collapsible bed-frame comprising side-members and end-members formed as longitudinal-channel bars having longitudinal flanges, pivot-pins passing through the flanges of said side- and end-members at adjacent ends thereof, and spacing-members maintaining the flanges of said side-members, at the pivoted ends thereof, in spaced relation with the flanges of the end-members. 125 130

5. A collapsible bed-frame comprising side-members and end-members formed as longitudinal-channel bars having longitudinal flanges, pivot-pins passing through the flanges of said side- and end-members at adjacent ends thereof, and spacing-members, through which said pivot-pins project, for maintaining the flanges of said side-members, at the pivoted ends thereof, in spaced

relation with the flanges of the end-members. 10

In testimony whereof, I affix my signature in the presence of two witnesses.

GEORGE L. HARPHAM.
